C. SHOLL

Removing Torpedoes.

No. 41,126.

Patented Jan. 5, 1864.

UNITED STATES PATENT OFFICE.

CHARLES SHOLL, OF BROOKLYN, ASSIGNOR TO F. A. DE MEY, OF NEW YORK, N. Y.

METHOD OF REMOVING SUBMERGED TORPEDOES.

Specification forming part of Letters Patent No. 41,126, dated January 5, 1864.

To all whom it may concern:

Be it known that I, CHARLES SHOLL, of the city of Brooklyn, in the county of Kings and State of New York, have invented a new method of removing or destroying torpedoes and other submerged or partly-submerged obstructions from harbors, rivers, and other waters; and I do hereby declare that the following is a full, clear, and exact description of the same, reference being had to the accompanying drawings, forming part of this specification, in which—

Figure 1 is a side view, illustrating my invention and its operation. Fig. 2 is a plan view of the same.

Similar letters of reference indicate corresponding parts in both figures.

This invention consists in the removal or destruction of torpedoes or other submerged or partly-submerged obstacles or obstructions from harbors, rivers, or other waters by throwing over them, from a mortar or mortars on board of a vessel placed at a suitable distance, one or more projectiles, which are furnished (or not) with hooks or other grappling devices, and are connected with the vessel by ropes or chains of suitable length, and then propelling the vessel in a direction to produce a draft upon said rope or chains and drag away or destroy the said obstacles or obstructions. By this means the vessel employed in removing the obstructions is prevented from being damaged by the explosion of torpedoes.

To enable others to apply my invention to use, I will proceed to describe it with reference to the drawings.

A is a vessel of the "monitor" or other construction, having arranged upon its deck, near one end, two mortars, B B, set at a suitable angle to each other—say about thirty degrees in a horizontal direction—and having a suitable elevation.

C C are two projectiles fitting the bores of the two mortars, and connected by a chain or rope, a, of wire or other material, to which, as well as to the projectiles themselves, are attached hooks b b, or other grappling devices.

D D are chains or ropes, of hide or other material, of suitable length, connecting the projectiles with capstans or bitts E E on the deck of the vessel. On the bow of the vessel

there may be a shot-proof or bomb-proof shield for the protection of the men working the mortars. In Fig. 2 the projectiles are shown in red color, not yet discharged, and the ropes or chains D D and a (shown in the same color) coiled upon the deck of the vessel, and in the same figure the projectiles are shown in black in their flight, and the ropes or chains D D and a are shown in the same color, extended as they are near the termination of their flight.

G G are torpedoes, and d d are the cables by which they are anchored or secured. e e is a net-work connected with the torpedoes, and f f are piles and other obstructions in the channel.

The operation is as follows: The vessel A is run up to within a safe distance of the first torpedoes or obstructions, and the mortars are loaded with suitable charges of gunpowder and the projectiles C C inserted, the ropes D D being suitably coiled on the deck of the vessel. The charges in the two mortars are fired simultaneously by a galvanic battery or other suitable means, and the projectiles, with their connecting chain or rope and attached hooks or grappling apparatus, are thrown over and beyond the torpedoes or other obstructions and allowed to sink, the rope or chain a having been extended by the divergence of the projectiles from each other, produced by the angle at which the mortars are set to each other, and the ropes or chains D D still connecting with the bitts or capstans E E, the charges of gunpowder used in the mortars only being sufficient to throw the projectiles far enough to extend the latter ropes or chains to a "taut" or nearly taut condition. The vessel is then run back to drag away the torpedoes or other obstructions, which are thus torn adrift, the torpedoes, in all probability, being at the same time exploded by the pull on the cords, wires, or chains connected with their locks. The explosion of the torpedoes thus produced takes place at such a distance from the vessel A as to be harmless to it. When the first obstructions have been removed, the vessel is run up the channel a suitable distance beyond the first advanced position, or to another suitable position, and the operation is repeated, and so on until all the

obstructions have been removed or destroyed. As many vessels may be employed in this way as may be desirable to remove or destroy the obstructions with desirable rapidity.

Instead of the two mortars, a double-barreled mortar having a single powder-chamber may be employed, the barrels being set at an angle to each other, like the two mortars hereinbefore described. By a mortar of this kind the simultaneous discharge of the two projectiles CC may be insured; or a single mortar and a single projectile might be employed in connection with a rope or chain secured at its ends to two vessels. In this case hooks or grappling devices may not be necessary.

What I claim as my invention, and desire to secure by Letters Patent, is—

1. The removal of torpedoes or other submerged or partly-submerged obstacles or ob-

structions from harbors, rivers, or other waters by throwing over them, from a mortar or mortars on board of a vessel placed at a suitable distance, projectiles which are connected with the vessel by one or more ropes or chains of suitable length, and then propelling the vessel in a direction to tighten the latter rope or ropes, or chain or chains, and drag away the said obstacles or obstructions, substantially as herein specified.

2. The combination of the vessel A, one or more mortars, B B, and projectiles C C, and the rope or ropes D D and *a*, or their equivalents, the whole arranged to operate substantially as and for the purpose herein specified.

CHARLES SHOLL.
